UNITED STATES PATENT OFFICE.

ROBERT JOHNSON AND AMEDEE MOREAU, OF NEW BEDFORD, MASSACHUSETTS.

EXPANSION REAMER.

Application filed May 15, 1922. Serial No. 561,243.

To all whom it may concern:

Be it known that we, ROBERT JOHNSON and AMEDEE MOREAU, citizens of the United States, residing at New Bedford, in the 5 county of Bristol and State of Massachusetts, have invented certain new and useful Improvements in an Expansion Reamer; and we do declare the following to be a full, clear, and exact description of the invention, such as will enable others skilled in the art to which it appertains to make and use the same.

This invention relates to an improved expansion reamer, and it has for its principal 15 object to generally improve upon devices of this class by providing one of extreme simplicity and durability which is such in construction as to permit accurate and fine adjustment of the cutting blades.

More specifically, it is another object of 20 the invention to produce a reamer of the above type wherein the blades are moved outwardly by novel means against the action of the spring fingers of a unique device 25 mounted on the body, these fingers co-acting with the opposite ends of the blades.

Other objects and advantages of the invention will be apparent during the course of the following description.

30 In the accompanying drawings forming a part of this specification and in which like numerals are employed to designate like parts throughout the same:

Figure 1 is an elevational view of a 35 reamer constructed in accordance with this invention.

Figure 2 is a central longitudinal sectional view thereof.

Figure 3 is a transverse section taken on 40 the line 3-3 of Figures 1 and 2.

Figures 4 and 5 are detail elevations of the expander and cutting blade respectively.

In the drawings, the numeral 1 represents an elongated cylindrical body which 45 is provided with a bore 2 opening through one end, the same being formed with internal screw-threads at its open end as shown. This body is also provided with a plurality of elongated circumferentially spaced slots 3 which communicate with the bore, there being a plurality of flat elongated cutting-blades 4 arranged in these slots and having their inner edges extending into the bore. As clearly seen in Figures 50 2 and 5, the cutting-blades have their

inner edges notched or cut to provide a plurality of spaced shoulders 5. In cutting the inner edges of these blades, the surfaces between the shoulders are inclined for co-action with the spaced conical members 6 of the longitudinally adjustable expander 7. The base portions of these conical parts 6 are adapted to abut the shoulders 5 when the blades are contracted to limit the movement of the expander in one direction. 65 Hence, after the device is once assembled, there is no liability of the expander being accidentally withdrawn from the bore in the body. While on this expander, it may be well to state that it is equipped at its outer 70 end with a screwthreaded portion 8 which co-acts with the threads at the outer open end of the aforesaid bore, together with a stop flange 9 and a flat faced wrench-engaging portion 10. By referring again to the 75 cutting-blades, 4 it will be seen that these are equipped at their opposite ends with notches 11 with which the free ends of the spring fingers 12 of the removable collars 13 co-act. It is the normal tendency of 80 these fingers to exert an inward pressure on the cutting-blades. However, the fingers are sufficiently resilient to permit full adjustment of the blades. The collars 13 are held in place by small set-screws 14 so as 85 to permit them to be removed whenever necessary to permit removal of the blades for sharpening. We are led to state here that in actual practice, the outer edges of the blades will be beveled from one flat-face to the opposite face to produce an extremely fine cutting edge. However, it is understood that they may be sharpened otherwise as it does not in any way affect the features of the invention. 90

Assuming that it is desired to radially expand the cutting-blades from the contracted position shown in Figure 2, it is obvious that by simply applying a wrench or the like to the part 10 of the expander 100 and rotating the latter to move it inwardly in the bore of the body, the conical parts 6 will act against the inclined surfaces of the cutting-blades to move them outwardly against the tension of the aforesaid spring fingers 12. As the expander is rotated to move it in the opposite direction, these fingers exert an inward pressure on the blades and automatically force them inwardly. 105

Although it is not essential, it is understood that in actual practice, the body 1 may be formed between the cutting-blades with elongated grooves 15 to serve as pockets 5 for collecting the shavings and to insure un-retarded rotation of the reamer when in use.

By carefully considering the description in connection with the drawings, persons familiar with device of this class will doubt- 10 less be able to obtain a clear understanding of the invention. Therefore, a more lengthy and detailed description is deemed unnecessary.

Since probably the best results may be 15 obtained with the construction and arrangement herein shown and described, this is taken as the preferred embodiment of the invention. However, we wish it to be understood that minor changes in coming within 20 the scope of the invention as claimed may be resorted to if desired.

We claim:

1. An expansion reamer comprising a body provided with a central longitudinal bore 25 and circumferentially spaced elongated slots communicating with said bore, blades arranged in said slots and having their inner ends extending into the bore, an expander cooperative with the blades for expanding 30 them, collars removably fitted on the body and embodying circumferentially spaced spring-fingers co-operative with the opposite ends of the blades for automatically moving them inward as the expander is withdrawn 35 from the bore.

2. An expansion reamer comprising a substantially cylindrical body formed with a longitudinal bore opening through one end

and provided at this end with screw-threads, 40 said body being provided with a plurality of circumferentially spaced elongated slots opening into said bore and terminating in spaced relation from the opposite ends of the body, a plurality of blades arranged in said slots, said blades being formed on their inner longitudinal edges with spaced shoulders connected by inclined surfaces, said blades being also notched at their outer ends, 45 an expander arranged in the bore and having its screw-threaded part engaged with the screw-threads in the latter, being also equipped with a stop-flange, a wrench-engaging portion, and spaced conical parts 50 co-operative with the inclined surfaces of said blades and collars arranged on said body, one at the outer end and one intermediate the ends, said collars being equipped with circumferentially spaced spring-fingers 55 co-operative with the notched ends of said blades for exerting an inward pressure on the latter.

3. An expandible reamer comprising a body having a plurality of recesses, blades seated therein, each blade having extensions at its ends forming shoulders, means 60 for causing the blades to move radially and collars mounted on the body and having spring fingers extending therefrom and engaging the shoulders at the ends of the blades for retaining the blades in the recesses.

In testimony whereof we have hereunto set our hands.

ROBERT JOHNSON.
AMEDEE MOREAU.
